DAVID A. DREW, OF PHILADELPHIA, PENNSYLVANIA.

Letters Patent No. 99,073, dated January 25, 1870.

IMPROVED CARPET-CLEANING MACHINE.

The Schedule referred to in these Letters Patent and making part of the same.

I, DAVID A. DREW, of Philadelphia, in the county of Philadelphia, and State of Pennsylvania, have invented certain Improvements in Machines for Cleaning Carpets and similar Fabrics, of which the following is a specification.

Nature and Object of the Invention.

My invention relates to machines made use of for cleaning carpets; and

Its nature consists in certain modifications in the details of the same, and in the combination and arrangement of the parts thereof, hereinafter described and shown.

The accompanying drawing represents a vertical longitudinal section of the machine.

General Description.

The rollers *a a*, held in close contact with each other by means of the lever *b* and weight *c*, revolve in opposite directions, as shown by the arrows, and thereby give motion to the endless cords *d*, which pass between them and similar rollers, *e e* and *f f*, and over carrying rollers *g h i*.

The bearings or journals of the roller *g* are made adjustable, so that, by its being moved to the left, the cords may be tightened.

The carpet, or other fabric, *k*, represented in the drawing by the red line, enters the machine at *l*, passes between the rollers at *e e*, over the roller *h*, between the rollers *f f* and *a a*, whence it falls on the floor, or other receptacle.

After passing the rollers *e e* and *h*, the fabric is subjected to a beating-process, by means of the beaters *m m*, oscillating on the shafts *m' m'*, their oscillation being produced in one direction by the cams *n n*, and in the other by either coiled springs *o* or coiled springs *p*, the fabric being held steady during the process by the rollers.

After the beating, the fabric passes between the

rollers *f f*, and is freed of most of the dirt and dust by the revolving cylindrical brush *r*, aided by a blast from the pipe *s*. This pipe is closed at the ends, but is provided with an opening or openings, running the entire length of the pipe, in such a manner that the blast will be directed between the fabric and the brush.

The pipe *s* is connected, by a branch or branches, *s'*, with a fan or blower, *t*, which produces the blast. The latter may consist of steam, superheated, and mixed with air, or it may consist of cold or hot air alone, the latter being usually employed, for the purpose of destroying moths and other insects.

The fabric passes now between two cylindrical revolving brooms, *u u*, and thence, after receiving a final brushing between the softer and shorter brushes *v v*, between the rollers *a a*, and out of the machine.

That part of the machinery which performs the cleaning-operation is enclosed, as far as practicable, by a nearly air-tight case, *w*, terminating at the top in a pyramid and flue, *x*.

The latter is provided with a damper, *y*, to regulate the escape of the heated blast, to some extent.

A spring may be used in lieu of the weight *c*.

Claims.

I do not claim, as my invention, any of the parts, abstractly; but

What I claim, is—

1. The arrangement of the levers *b*, weights *c*, rollers *a a*, *i*, *g*, *e*, *h*, and *f f*, endless cords *d*, cams *n n*, and beaters *m m*, as herein described and shown.

2. The combination and arrangement of the brush *r*, fan *t*, branch-pipes *s* and *s'*, broom *u u*, and brushes *v v*, as herein described and shown.

DAVID A. DREW.
